CLOSURE FOR CONTAINERS

Application filed July 18, 1927. Serial No. 206,642.

The invention relates to improvements in closures and more particularly to hinged closures.

The invention has as one of its objects to provide a closure for containers distinguished by its simplicity of construction and operation which not only enhances its value mechanically but commercially as well.

My invention concerns itself more specifically with that type of container known as the collapsible tube wherein the closure is not only permanently and hingedly mounted upon the tube, but is capable of rotation relative thereto to subject the closure to a sealing pressure upon the container, and to this end my invention contemplates a construction wherein the parts which serve to hingedly attach the closure upon the container are also utilized, upon rotation of the closure, to effect a firm and sealed seating of the closure in its closed position upon the container.

While in particularizing upon the advantages and features of the present invention particular stress has been placed upon the association of the closure with a collapsible container, and while the illustrative embodiment of the invention herein shown and described is adapted for use with such a container, nevertheless the objects of the invention may be accomplished with various other forms of containers and the invention therefore contemplates such an arrangement.

Many of the advantages and much of the commercial value and acceptability of the invention is attributed to the novel construction of the closure and the mounting thereof upon the container, these advantages being obtained particularly because of the simplicity of the device and the facility with which it may be assembled. The invention, therefore, depends for some of its advantages upon the specific details of construction illustrated and about to be described.

Other objects and novel features of construction which contribute materially to the efficiency of the apparatus will be made more apparent as this description proceeds especially when considered in connection with the accompanying drawings wherein:

50 Figure 1 is a side elevation of a container

equipped with the herein disclosed closure;

Figure 2 is a view similar to Figure 1 showing the closure in open position;

Figure 3 is a perspective view showing the closure and container before assembly; 55

Figure 4 is a fragmentary elevation of the container with the closure removed.

Figure 5; is a sectional view taken on the line 5—5 of Figure 4.

Referring now particularly to the drawings wherein like reference characters designate corresponding parts throughout the several views, it will be noted that there is illustrated a container 10 having a reduced neck portion 11 formed with a suitable opening 12 60 for establishing communication with the interior of the container. The neck portion 11 is further provided with a laterally extending projection or lug 13 and the diametrically opposed cam grooves 14 and 15. As shown 65 particularly in Figure 2 these grooves preferably extend circumferentially of the neck portion and terminate a suitable distance from each other forming the stops 16 and 17. The grooves are preferably, although not necessarily pressed into the neck portion 11 70 and are inclined to a corresponding degree in opposite directions.

For closing the opening 12 in the container 10 a cup shaped closure 18 is provided. As 80 shown in Figure 3 the skirt portion 18' of the closure is provided with a slot or aperture 19 for receiving the lug 13. In order to prevent any escape or removal of the closure from its described position upon the neck portion 11 85 the lug 13 is bent upwardly as clearly illustrated in Figure 2. The inner surface 13' of the projection 13 is spaced a suitable distance outwardly from the periphery of the neck portion 11, and the length of the projection 13 is such that when the closure 18 is 90 swung to closed position, the projection will assume a position exteriorly of the closure as clearly illustrated in Figure 1. In other words, the above construction is such that 95 when the closure is swung to closed position, the wall 18' thereof assumes a position between the inner surface 13' of the projection and the periphery of the neck portion 11 rendering possible the necessary rotation of the 100

closure 11. Formed integral with the lower edge of the closure in diametrically opposed relation are the cam members 20 and 21 engageable respectively in the cam grooves 14 and 15. As shown the cam member 20 is in direct vertical alignment with the aperture 19 and together with the lug 13 and the curved inner wall of the groove 14 serves to hingedly connect the closure to the container. To permit the cam member 21 to register with the groove 15 when the closure is swung to its closed position the neck portion 11 is formed with a slot 22 diametrically opposite the lug 13.

15 In order to insure a proper seal between the container and closure when the latter is in its closed position a cork disk 23 is non-removably secured in the closure 18. Thus when the container is not in use the contents 20 thereof is efficiently preserved from the surrounding atmosphere.

Assuming that the closure is in the position shown in Figure 2 and it is desired to close the same the cap 18 is swung down upon the container, the cam member 20 acting as a pivot for the hinge and the cam member 21 passes through the slot 22 into registration with the groove 15. As heretofore pointed out, when the closure is swung to its closed 30 position the lug 13 passes through the slot 19 and assumes a position exteriorly of the cap as shown in Figure 1 thus permitting the closure to be rotated in a clockwise direction and by virtue of the inclined cam grooves 14 and 35 15 the closure is subjected to a downward pressure whereby the cork disk 23 will be compressed between the closure top and the top portion of the neck establishing a tight seal. The closure is prevented from excessive rotation in either open or closed position 40 by means of the stops 16 and 17.

From the foregoing it will be readily apparent that the herein described closure is permanently and hingedly attached to the container and the cam member 20 not only cooperates with the curved wall of the cam groove 14 to form a pintle for the hinge member 13 but also to subject the closure to a sealing engagement with the container. Thus 50 a dual function may be attributed to the cam member 20. Furthermore the whole construction lends itself to economy in construction, simplicity in operation and assembly.

While the invention has been described in 55 connection with a closure for use with a collapsible container, it will be apparent that the invention is broader than this in its scope and may be employed with equal facility upon various other forms of containers. There- 60 fore reservation is made to make such changes in the details of construction as may come within the purview of the accompanying claims.

What I claim as my invention is:

65 1. The combination of a container having

an opening therein and having oppositely inclined circumferentially extending cam grooves, a hinge member associated with one of said grooves, and a rotatable closure for said opening having inwardly extending cam 70 members cooperating with said grooves upon rotation of the closure to subject the latter to a sealing pressure upon the container, one of said cam members co-acting with the hinge member aforesaid to exercise a hinge function 75 for the closure in one rotatable position thereof.

2. The combination of a container having an opening therein and having oppositely inclined circumferentially extending cam 80 grooves, a rotatable closure for said opening having cam portions and having a slot adjacent one of said cam portions, said cam portions being arranged to cooperate with the cam grooves upon rotation of the closure to 85 subject the latter to a sealing pressure upon the container, and a member projecting from said container arranged to extend through the slot formed in said closure upon movement of the latter to open position to form a hinge 90 therefor.

3. In combination, a container having an opening therein and having an inclined groove adjacent to said opening, a member normally closing said opening having a cam 95 portion engaging said groove, and a projection upon said container engageable with said cam portion to maintain the same in said groove in one rotative position of the closure and to cooperate therewith in another rotative 100 position thereof to form a hinge for said closure.

4. In combination, a container having an opening therein, a closure normally closing said opening, means operable in one rotative 105 position of the closure to subject the same to a sealing pressure upon the container, and an extension upon said container operable upon movement of the closure to open position to project through an aperture formed in one 110 wall of the latter and form a hinge therefor.

5. In combination, a container having an opening therein, a projection carried by said container, a closure for said opening, the said closure being rotatably mounted upon said 115 container and being provided with an aperture in one wall thereof adapted to register with the said projection upon a predetermined rotation of the closure, the said projection being so arranged as to project through the aperture and cooperate with a portion of said closure to form a hinge therefor upon movement of the same to open position.

6. In combination, a container having an opening therein, a closure for said container having an aperture in one wall thereof, means 120 permitting rotation of said closure upon said container, and a projection upon said container normally disposed exteriorly of the closure and adapted to project through the 125 130

- aperture aforesaid upon movement of the closure to open position to form a hinge for the said closure.
7. In combination, a container having an opening therein, a closure for said opening rotatably mounted upon said container, said closure having an aperture in one wall thereof, and a hinge for said closure including a fixed part upon the container adapted to fit in the aperture aforesaid in one rotative position of the closure to establish a hinge connection between the latter and the container.
8. In combination, a container having an opening therein, a closure for said opening rotatably mounted upon the container, said closure having an aperture in one side wall thereof, and a projection upon said container adapted to register with the aperture aforesaid to establish a hinge connection between the closure and container in one rotative position of the closure and in another rotative position of the latter to be out of registration with said aperture.
9. In combination, a container having a neck provided with an opening, and a substantially C-shaped lug projecting laterally from said neck adjacent to said opening, a closure for said opening including a rotatable cap having a skirt portion movable about the periphery of said neck and apertured to receive and move longitudinally of the lug aforesaid of said container to permit said cap to hinge upon said neck and uncover said opening.
10. In combination, a container having a neck portion provided with an opening, a closure for said opening including a cap rotatable upon said neck and movable in the arc of a circle in a plane at substantially right angles to the plane of rotation to uncover said opening, and a fixed part on the periphery of said neck extending over the outer face of said cap when it is in a position to rotate upon said neck, and receivable in an aperture of and constituting a hinge for said cap when it is moved in the arc of a circle as aforesaid.
11. In combination, a container having a neck provided with an opening, a closure for said opening including a cap having a portion for closing said opening and having a skirt portion for embracing said neck, said cap being rotatable upon said neck and being movable in the arc of a circle in a plane at substantially right angles to the plane of rotation to uncover said opening, means normally maintaining said cap in closed position including separable cam elements carried respectively by said neck and skirt portions and normally in operative cam engagement with one another, and a separable hinge connection between said cap and container including parts carried respectively by said container and cap and normally disengaged but adapted, when the cam elements aforesaid are disengaged from one another and said cap is moved in the arc of a circle as aforesaid, to have interlocking hinge connection with one another.
12. In combination, a container having a neck provided at one end with an opening, a lug projecting from the container and having an end portion substantially parallel to said neck, and a closure for the opening including a rotatable cap having a portion for closing said opening and having another portion adapted when said cap is rotated to move about the neck to a position between the end portion of said lug and said neck, said skirt portion having an opening that is adapted when said cap is in the position of rotation aforesaid to receive said lug and permit the cap to hinge upon said lug to uncover said opening.
- In testimony whereof I affix my signature.
- CECIL R. CRARY.
